UNITED STATES PATENT OFFICE.

HERBERT D. FLEMING AND LEO F. MATTHEWS, OF NEW KENSINGTON, AND EDGAR C. FLEMING, OF RENFREW, PENNSYLVANIA.

COMBINED TOBACCO CONTAINER AND MATCH RECEPTACLE.

Application filed March 13, 1922. Serial No. 543,499.

To all whom it may concern:

Be it known that we, HERBERT D. FLEMING, LEO F. MATTHEWS, and EDGAR C. FLEMING, citizens of the United States, residing at 5 New Kensington, Westmoreland County, Pennsylvania; New Kensington, Westmoreland County, Pennsylvania; and Renfrew, Butler County, Pennsylvania, respectively, have invented certain new and useful Im- 10 provements in Combined Tobacco Containers and Match Receptacles, of which the following is a specification.

This invention relates to tobacco user's appliances and the primary object of the 15 invention is to provide a combined match receptacle and tobacco can or container so that the two articles can be dispensed as one and so that the matches will always be in a handy place for use.

20 A further object of the invention is the provision of a match receptacle combined with a tobacco can having novel means for removably holding matches of the strip type, that is, paper matches which have 25 their bases integrally connected together, in place therein, so that when the matches are used up, the connecting base of the same can be removed and a new strip of matches inserted in place in lieu thereof.

30 A further object of the invention is the provision of a combined tobacco can and match receptacle connected together in any desired manner, the match receptacle being 35 preferably made from stamped metal and embodying a rear supporting wall, integral side walls, a hinged front wall for covering the strip of matches, and a resilient top wall integrally connected with the rear supporting wall, the top wall being so formed as to 40 form means for holding the hinged front wall in its closed position, and means for holding the strip of matches removably in place.

With these and other objects in view, the 45 invention consists in the novel construction, arrangement and formation of parts, as will be hereinafter more specifically described, claimed and illustrated in the accompanying drawings, forming a part of this specification, in which drawings:

Figure 1 is a detail perspective view of the combined match container and match box, the cover for the match box being shown in its open position.

50 Figure 2 is an enlarged fragmentary ver-

tical section through the improved match box and tobacco container, showing the front wall of the match box in its closed position.

Figure 3 is a similar view showing the front wall of the match box in its open position and the strip of matches removed from the box.

Figure 4 is an enlarged fragmentary horizontal section through the improved match box and tobacco container.

Referring to the drawings in detail, wherein similar reference characters designate corresponding parts throughout the several views, the letter A indicates the tobacco container; and B, the improved match 70 box or receptacle.

The tobacco container A can be of the ordinary type, now used in vending tobacco, and as shown consists of an elongated rectangular body 5 having one end closed by a 75 hinged lid 6. The front wall 7 of the body 5 is adapted to support the match box B, which can be welded, soldered or otherwise secured thereto. It is to be, of course, understood, that the match box B can be secured 80 in place, in any preferred manner on the tobacco container and at any preferred point, such as the rear wall thereof.

The match box B is of novel construction, and is particularly adapted to removably 85 support matches of the strip type, that is, matches constructed of paper and integrally connected together at their bases. In the drawings, the match strip is indicated by the reference character C and includes the integral base strip 8 and the match sticks 9.

The match box or receptacle B includes a rear connecting wall 10, which as stated, can be secured in any preferred manner to the tobacco container A, and the lower edge of 95 this wall 10 is preferably bent outwardly as at 11 and provided with a hinge barrel 12. The vertical side edges of the rear wall 10 are bent forwardly in parallel relation to provide side walls 13 as clearly shown in 100 the drawings. It is also preferred that the upper edge of the rear wall 10 be bent to provide the upper wall 14. The upper wall 14 is of novel construction and forms an important part of the invention and will be 105 later described in detail.

The match box B is provided with a front wall 15, which is adapted to lie in spaced parallel relation to the rear wall 10. The lower edge of the front wall 15 is bent in- 110

- wardly as at 16 and provided with a companion hinge barrel 17 for the hinged barrel 12 carried by the rear wall 10 and these barrels are adapted to receive a hinge pin 5 or pintle 18. As clearly shown in Figure 4 of the drawings, the front wall 15 is adapted to lie between the side walls 13 and is arranged to snap under the resilient top wall 14 which will now be described.
- 10 The top wall 14 at its point of connection with the rear wall 10 is bent into a substantially inverted U-shaped form to provide a resilient flange 19, which is adapted to frictionally engage the base strip 8 of the 15 match strip C, in order to removably hold the match strip C in position. It is obvious that by grasping the forward edge of the top wall 14, that the same can be flexed in order to move the flange 19 from out of engagement with the base strip 8 to permit a new strip of matches to be inserted in the match box. The extreme forward edge of the top wall 14 is bent to form a bead 20, which is adapted to receive the upper edge 25 of the front wall 15 and hold the same in its closed position against accidental opening movement. It can be seen that when it is desired to open the front wall 15 it is merely necessary to slightly flex the top wall 14. This is not necessary, however, as the front wall can be simply given a sharp pull forward which will automatically flex the top wall 14. In order to facilitate the opening movement of the front wall 15, a struck 30 out lug 21 can be formed in the front wall and thus the lug constitutes a finger piece. Thus it can be seen that by grasping the finger piece or the lug 21, the front wall can be readily swung open.
- 35 From the foregoing description, it can be seen that a combined tobacco container and match box has been provided of simple and durable construction, which will form a compact unitary article and in which the matches are so held that the same will be in a convenient place at all times for ready use.
- 40 Changes in details may be made without departing from the spirit or scope of this invention; but,
- 45 We claim:
1. The combination with a tobacco box, of a match receptacle secured to one wall
- thereof embodying a rear supporting wall, side walls, a resilient top wall, and a hinged 55 front wall, the resilient top wall being adapted to hold the front wall against opening movement and to hold a strip of matches in position against accidental removal.
2. In a tobacco user's appliance, a tobacco 60 box formed of sheet metal including a rear wall, a front wall hingedly connected to the rear wall, side walls, and a resilient top wall arranged to engage the upper edge of the front wall to hold the same in closed position against accidental opening movement, and a resilient flange formed on the top wall for frictionally engaging a strip of matches.
3. In a tobacco user's appliance, a match 65 box formed of resilient sheet metal including a rear wall, side walls formed on the side edges of the rear wall, a front wall, the lower edges of the front and rear walls being provided with companion hinged barrels, a pintle extending through the barrels, a 70 resilient top wall formed on the rear wall, a bead formed on the front edge of the top wall for receiving the hinged front wall, and a resilient clip formed on the top wall for receiving the base portion of a strip of 75 matches.
4. In a tobacco user's appliance, a match 80 box formed of resilient sheet metal including a rear wall, side walls formed on the side edges of the rear wall, a front wall, the lower edges of the front and rear walls being provided with companion hinged barrels, a pintle extending through the barrels, a 85 resilient top wall formed on the rear wall, a bead formed on the front edge of the top wall for receiving the hinged front wall, a resilient clip formed in the top wall for receiving the base portion of a strip of 90 matches, and a struck out finger piece 95 formed on the hinged front wall.
5. A match receptacle embodying a rear supporting wall, side walls, a resilient top wall, and a hinged front wall, the resilient top wall being adapted to hold the front wall against opening movement and to 100 frictionally retain a strip of matches in position against accidental removal.
